DESIGN FOR A DISPLAY DISPENSER

Russell G. Jones, Reading, Mass., assignor to William B. Berry Company, Boston, Mass., a corporation of Massachusetts

Application November 22, 1946, Serial No. 135,020

Term of patent 7 years

(Cl. D52—3)

To all whom it may concern:

Be it known that I, Russell G. Jones, a citizen of the United States, residing at Reading, in the county of Middlesex and Commonwealth of Massachusetts, have invented a new, original, and ornamental Design for Display Dispenser, of which the following is a specification, reference being had to the accompanying drawing, forming part thereof.

Figure 1 is a perspective view of a display dispenser showing my new design and viewed from the front.

Figure 2 is a similar view as Figure 1 but as seen from the rear, and

Figure 3 is a top plan view.

The essential features of my design reside in the portion shown in full lines.

I claim:

The ornamental design for a display dispenser, substantially as shown and described.

RUSSELL G. JONES.
